Primary Examiner—Cathy Anne MacCormac*Attorney, Agent, or Firm*—Joseph N. Breaux[57] **CLAIM**

I claim the ornamental design for a pet bed, as shown and described.

DESCRIPTION

FIG. 1 is a perspective view of a pet bed showing my new design;

FIG. 2 is a right side elevational view thereof, the left side being a mirror image;

FIG. 3 is a front elevational view thereof;

FIG. 4 is a rear elevational view thereof;

FIG. 5 is a top plan view thereof; and,

FIG. 6 is a perspective view of the rear of the pet bed showing the fold down compartment lid seen in FIG. 4 in open position.

The bottom is plain and unornamented.

1 Claim, 3 Drawing Sheets

FIG. 1.

FIG. 2.

FIG. 3.

FIG. 4.

FIG. 5.

FIG. 6.
